SHOWER MAT

Maurice H. Kraines, Los Angeles, and Robert L. Unkrich,
Long Beach, Calif.; said Unkrich assignor to said
Kraines

Filed Dec. 26, 1961, Ser. No. 68,058

Term of patent 14 years

(Cl. D9—6)

It is to be understood that the surface texture fragmentarily shown in FIGURE 1 covers the entire areas designated.

We claim:

The ornamental design for a shower mat, substantially as shown and described.
